UNITED STATES PATENT OFFICE.

PHILIPP CHARLES CLOSE, OF AUGUSTA, GEORGIA.

SEWAGE AND NIGHT-SOIL DESICCATING APPARATUS.

SPECIFICATION forming part of Letters Patent No. 380,383, dated April 3, 1883.

Application filed February 4, 1887. Serial No. 226,595. (No model.)

To all whom it may concern:

Be it known that I, PHILIPP CHARLES CLOSE, a citizen of the United States, residing at Augusta, in the county of Richmond, State of Georgia, have invented certain new and useful Improvements in Sewage and Night-Soil Desiccating Apparatus, of which the following is a specification, reference being had therein to the accompanying drawings.

- 10 My invention relates to improvements in apparatus for desiccating human excrements, in which hot air and fire are used from time to time to convert this fecal matter into a trans-
portable and inoffensive residuum of value as
15 a fertilizer; and the objects of my improvements are to produce a substitute for privies and water-closets essentially inodorous and innocuous as a receptacle for collecting and retaining this fecal matter, and also during the opera-
20 tion of its disposal by hot air and fire, in a simple, economical, and effective manner, by conducting the odors and exhalations by a continuous draft into a properly-constructed flue open to the air, while standing cold or
25 during the collection, and by the destruction of all odors in applying the hot air, fire, and lime. I attain these objects by the construction illustrated in the accompanying drawings, in which—
30 Figure 1 is a vertical section through an apparatus constructed in accordance with my invention. Fig. 2 is a longitudinal vertical section of the portable furnace forming a part of the apparatus. Fig. 3 is a longitudinal ver-
35 tical section of a stationary retort to receive the excreta or night-soil. Fig. 4 is a trans-
verse vertical section of the same. Fig. 5 is a horizontal section of the furnace.

In said drawings, A represents an oblong 40 flat-shaped retort, preferably made of cast-iron and retained vertically by resting on the bottom, and steadied by suitable braces in the chamber B, made of brick or other suitable fire-proof material, as shown in Figs. 1, 3, and
45 4. When the privy-seat b is located in an upper story, as in Fig. 1, the retort is connected thereto by suitable and properly-constructed pipes of cast-iron. This seat may be left un-
covered; or if closed with a cover, b², it is

best to leave a small opening for admission of 50 draft to the main flue B³. If the privy-seat is on the same floor as the retort, the draft passes downward at b⁷ through the seat-hole, and all other "dampers" or vents for draft are closed while collecting this excreta, which is depos- 55 ited or dropped through the hole in privy-seat into the mouth of retort. The openings of these seats, and also the top opening or mouth of retort, are directly connected with a flue or chimney, B³, that extends to a height at least 60 twenty times its diameter, and this diameter or draft-surface is to be equal to the draft-surface of fire-box.

When the contents of retort are to be desic- 65 cated, the inlet-opening b³ is used to direct the products of combustion—heat and smoke—through a short flue from a furnace, D, hereinafter described.

In the bottom of the retort there is a remov- 70 able horizontal partition, a, to support its con-
tents; but said partition has fine perforations
for the passage of hot air and for the straining
off of the urine, which is valuable for its nitro-
gen compounds, which may be drawn off 75 through a pipe, a², controlled by a cock con-
nected to the hot-air pipe. Under the parti-
tion a a pipe, a³, is placed horizontally to bring
into the retort a current of hot air or of in-
flammable gases from the furnaces D. Secured 80 to the inside of the retort, near its open mouth,
are brackets to support a perforated plate, a⁴,
that is placed thereon at the time the contents
are to be desiccated, said plate being to sup-
port, first, a layer of unslaked lime to decom- 85 pose the sulphureted hydrogen escaping from
the retort by absorbing its sulphur and pro-
ducing sulphide of lime, and releasing the hy-
drogen that is destroyed in its passage through
a layer or column of (burning) charcoal that 90 has been placed upon the lime. This char-
coal is ignited through an opening, a⁵, cut out
from the top on the side of retort by the flame
or heat that passes with the draft through it
and across the mouth of retort through pas- 95 sage a⁶ on its way to the main flue. After
this charcoal is once ignited its combustion is
kept up by the current of hot air passing up
through the retort. The valve a⁹ being closed,

the draft is returned, so that the gases from the inside of retort passing out of the mouth are carried toward the outlet-opening B^3 , thence downward with the heat from furnace 5 through the flue surrounding the retort, and are thus destroyed.

To remove the desiccated contents of the retort, the lower part is provided with openings that are closed by cap-plates c , retained by 10 clamps c^2 and screws c^3 bearing firmly against said plates. These plates are made to fit tightly with suitable packing, so as to hermetically seal the bottom of retort.

To produce the desiccation of the contents 15 of the retort and their transformation into a valuable fertilizer, the furnace D is used. It is preferably mounted on wheels d , and is a rectangular box of metal, made either with double walls or with a lining of fire-brick or 20 clay. It has a grate, E, near the bottom thereof, to support the combustibles when wood or coal is used to produce the necessary heat, the ash-pit F being under the grate.

To send a certain amount of highly-heated 25 air or of inflammable gases through the pipe a^2 into the bottom of the retort and through the contents of said retort, a continuous coil of pipe, i , is placed within the furnace around its sides, and said coil is connected at one end 30 with pipe i^2 , issuing from the bottom of air-pump H, and at the other end with pipe a^3 in the bottom of retort.

When it is desirable to use inflammable gases in connection with wood or coal fuel, for 35 the purpose of increasing the evaporating heat in the mouth of retort, oil or other gas-producing liquid is placed in a vessel, so as to gradually enter the pump at its point of suction, and then is forced drop by drop by this 40 pump into the heating-coil of pipe on the inside of the furnace. Thence the gas formed from this oil is forced into the bottom of the retort, ascends through the contents of retort to flame and blaze in the mouth of retort on 45 coming in contact with oxygen and the burning charcoal; but hydrocarbon liquids can also be used independently of solid combustibles, or in connection therewith, to increase the length of the flame issuing from the furnace and passing around and under the retort. 50 For this purpose a tank, G, is placed upon brackets d^2 , secured to the top of the furnace, and from the bottom of the tank issues a pipe, g , that leads the liquid into a series of horizontal pipes, g^2 , entering one end of the furnace and extending across it. They have small perforations in their sides to let the liquid hydrocarbon escape and fall drop by drop upon the incandescent coal in the bottom of 55 the furnace; and to furnish a fresh supply of air there are placed directly under each pipe g^2 a similarly-perforated pipe, h , leading from a hand-blower or pump, said pump having the pipe h^2 leading into each one of the horizontal air-pipes h .

In the passage or flue between the retort and its casing a valve, K, is placed to regulate the amount of draft and heat passing therethrough.

Although the drawings show the entrance of 70 the heat-flue from furnace at but one point near the top of retort, it is evident that this opening b^2 can be placed at any point along the sides, or to the rear or the front of retort. Ebullition of the contents being prevented by 75 the current of hot air, and the temperature of the heat required in the outside of retort being only high enough to prevent the condensation of the vapor with the hot air in its passage through the retort, a temperature above 400° 80 Fahrenheit of the air is to be avoided, as it is likely to decompose the nitrogen compounds of the contents of retort.

It is evident that there must be a separate flue for each retort to preserve intact the physical principles by which a thousand cubic feet of fresh to one of foul air is supplied while standing cold and collecting this fecal matter by a continuous draft just across the mouth of retort, and that separate flues are as necessary in the desiccation by fire, while the portable furnace can be used for any or a great number of retorts.

Having now fully described my invention, I claim—

1. The combination of a retort having a perforated plate, a^4 , in the top, a perforated plate, a , in the bottom, and a pipe to admit air under the bottom plate, with a casing inclosing said retort, and having flues to conduct a current of the production of combustion and heated air across the top and down one side and upward on the opposite side of said retort, substantially as described.

2. The combination of a vertical retort having a perforated plate in its upper and in its lower end, a casing inclosing said retort, and a furnace having supporting-wheels and a pipe upon one side connecting with said casing, whereby the products of combustion are directed down one side of the retort, substantially as and for the purposes described.

3. The combination of a vertical retort and its casing, separated by flues between them, with a furnace having the horizontal pipes g^2 within said furnace, and a tank, G, connected with said pipes, substantially as and for the purposes described.

4. The combination of a vertical retort and its casing with a furnace, a pipe connecting said retort and furnace, the tank G, having a discharge-pipe with lateral perforated branches within said furnace, the air-pump H, and the horizontal pipes h , substantially as and for the purpose described.

5. The combination of a vertical retort, having a perforated plate, a , in the bottom thereof, and the pipe a^3 under said plate, with a furnace having a continuous coil, i , therein, an air-pump, and a pipe to connect said pump

and coil with the pipe a^3 in the bottom of the retort, substantially as and for the purposes described.

6. The combination of a vertical retort, having a perforated plate, a , and the pipe a^3 , with a furnace and coil, i , an air-pump and connecting pipe, and a vessel or reservoir for gas-producing liquids connected with said pump at

its point of suction, substantially as and for the purposes described.

In testimony whereof I affix my signature in presence of two witnesses.

PHILIPP CHARLES CLOSE.
